MULTIPLE TUBE TIRE AND INDICATOR

Siegfried Libo, Milwaukee, Wis.

Application October 27, 1933, Serial No. 695,528

3 Claims. (Cl. 152—22)

It is the purpose of this invention to provide a new kind of pneumatic inner tube combined with a device, which will lose only a small fraction of its air pressure when punctured, blown out or otherwise damaged; further to afford a comparatively smooth easy driving on, although a puncture, blowout or other similar damage has occurred to the inner tube, thereby avoiding the great dangers and risks of total blowouts in the present used inner tubes, and the dangers and the disagreeable test of repairing or changing an inner tube when on a street or road as any puncture or blowout which might occur, will cause only a slight flattening of the inner tube or the outer casing respectively, and will not be sufficient to prevent the tire acting properly, until the machine may have been driven to a convenient place, where a new inner tube may be inserted or the old one repaired.

One improvement of my invention is, to provide an inner tube with a plurality of cells (chambers). If one of the cells becomes punctured or otherwise damaged so that the cell loses its air pressure, the opposite partition walls of the cell will instantly close up the gap.

A further improvement of my invention is, that each cell has its own individual hose (air passage), but the inflation of all cells is simultaneously accomplished by a device in conjunction with a valve outfit.

A further improvement is, that all hoses (air passages) are built into a single collar (neck), but the openings of the hoses (air passages) in same are kept separate.

A further improvement of my invention is an arrangement on the device in conjunction with the pneumatic inner tube, which automatically indicates if a cell has become punctured, blown out or otherwise damaged, so that the cell lost its air pressure.

Another improvement of my invention is a consecutive numbering arrangement, which indicates precisely and immediately if, and which specific cell or cells have become punctured, blown out or otherwise damaged and lost their air pressure.

A further improvement of my invention, is the simple manner of closing up of a hose-opening (air passage) in the collar (neck), which leads to a punctured or otherwise damaged cell.

An advantage of my invention is also, that a longer usage of the inner tube and casing will be afforded, as any blowout which might occur, will practically be confined to a single cell, and the small volume of air pressure contained in one of the cells (chambers) would find sufficient room

to expand and lose its force without damaging or rupturing the outer casing.

The form of my invention is illustrated in the accompanying drawings, in which Fig. 1 is a sectional side elevation of a tire provided with my improvement, showing the pneumatic inner tube with the arrangement of the semi-ellipsed shaped partition walls and showing in dotted lines where some of the hoses (air passages) commence from the cells.

Fig. 2 is a similar view, showing one cell (chamber) punctured or otherwise damaged with no air pressure, and the resulting gap closed up by the two opposite semi-elliptical shaped partition walls through the air pressure forced on same partition walls by the opposite and adjacent cells.

Fig. 3 is part of a cross section of the inner tube, tire and rim.

Fig. 4 is a sectional view of the device in conjunction with the pneumatic inner tube and showing part of the inner tube.

Fig. 5 is a sectional view of a metal tube with inserted rubber tube.

Fig. 6 is a view of the device looking downwards from the top, with dustcap, washers and screwnut around the casing removed.

Fig. 7 is a view of how the lower disc in the casing is kept in place to avoid any sideway movements.

Fig. 8 is a view of a plugscrew inserted in the lower disc, and a metal tube with a closed head over it and screwed into the upper disc. (This special plugscrew and closed end metal tube are used only in cases where a puncture to a cell has occurred, and more air pressure is wanted in the other cells, without repairing the punctured one.)

Considering the drawings in detail, 1 in Fig. 1 is the pneumatic inner tube for tires into which are built in a plurality of semi-elliptical (or semi-circular or like) shaped partition walls 2, which form equally sized cells (chambers) 3, with hoses (air passages) 4, leading into said cells. Each of these hoses (air passages) continuous on the inner circle of the inner tube in the thickened bed 5 formed, as shown in Figure 3. All hoses (air passages) lead also and are built into a common circular collar (neck) 7, but each hose has its opening kept separately on top of collar (neck).

In the inner tube for instance shown in Fig. 1, there are thirteen equally sized cells, and were the inner tube 17" in diameter, each cell would be about 4" long. If one cell becomes punctured or otherwise damaged, so that the cell lost its

air pressure, the air pressure in the remaining cells will cause a certain endwise expansion (movement) of the partition walls, and especially the air pressure on the center of the semi-elliptical shaped partition walls opposite of the damaged cell will facilitate and immediately tend to close up the gap 9, (the cell without air-pressure) as shown in Fig. 2; this closing of the gap being also partly due, to the weight imposed on the tire, thereby tending to flatten the tire, the inner tube and the not punctured cells respectively.

If a greater amount of cells is desired, the number of hoses (air passages) etc. must also be increased correspondingly.

In the center of the collar (neck) 7, a bolt 11 is provided which has adjacent to its head a square part 13. Said head of bolt is embedded in a suitable manner in the inner tube and collar respectively, as shown in Fig. 4. Four screws 16 are provided to hold in place the projections 20 forming obtuse angles 21 and the casing 23 when the screwnuts 24 are applied. Any other suitable similar way may be employed to hold the circular casing firmly in place to the inner tube. Where the thickened bed 5 of the inner tube leads into the circular casing 23, openings 27 are provided on opposite sides on the circular casing between the lower extension of same to let the thickened bed pass into the circular casing, where it meets and is incorporated in the collar (neck). The collar which is formed by the hoses, inner tube and thickened bed, rests on its outer diameter on the circular projection 29 on the inside 35 of casing 23, and on its inner diameter on the underside of the head of bolt 11.

Around bolt 11, a disc 30 is provided, which rests on top of collar 7. Same disc has an identical amount of threaded hole openings 31, ending in lips 32, these lips fitting tightly into the hose openings on top of collar 7. Said disc further extends from its inner bottom diameter 33, first vertical 34, then horizontal 35, and fits around the square part 13 adjacent to the underside of the head of bolt 11. With a hexagonal screwnut 36, which is placed around the threaded part 37, adjacent to the square part 13 of bolt 11, the previously mentioned disc is tightened down on top of collar 7, so as to obtain an airtight closure of the spaces between the lips and the top of collar.

On two opposite places said disc 30 has on its outer bottom diameter a vertical 38 and horizontal 39 cutout (notch), into which the inside projections 40 of casing 23 seat into, as shown in Figures 4 and 7.

The previously mentioned cutout (notch) on the bottom of the outer diameter of disc 30, and the projections 40 on the casing, in conjunction with the vertical and horizontal extension on the bottom of the inner diameter of disc 30 fitting around the square part 13 of bolt 11, are for the purpose, so after disc 30 is screwed down by nut 36, disc 30 and bolt 11 will be prevented from turning sideways.

Over the previously mentioned disc 30, there is another disc 41 with an identical arrangement of threaded hole openings 42, but larger diameter, as shown in Figures 4, 5 and 8, and in addition there is an opening 43, over and on which a suitable complete valve outfit 44 is provided. Another opening 45 is provided in the center of disc 41 for letting through bolt 11. Top of disc 41 is also provided with two horizontal parts 47 on vertical projections (lugs) 48 in which moves the

bottom projection (flange) 49 of a tubular screw 50. This flange on the tubular screw fits loosely into the mentioned lugs on top of disc 41. The previously mentioned tubular screw has a closed hexagon head 51, and a knurled part 52 on the circular projection 53 to facilitate screwing by hand or suitable tool. When tubular screw is placed around thread 54 of bolt 11 and screwed downward or upward, the arrangement of the lugs 48 on top of disc 41, in which the flange 49 of the tubular screw moves freely, and in conjunction with the vertical extension 55 on bottom of same disc, which fits closely around the square part 56 of bolt 11, will prevent sideway turning of disc 41. In the depression on the inside diameter of disc 41, a packing 58 is provided, which closes up airtight the space between the inner diameter of disc 41 and bolt 11. In the depression 59 on the outside of disc 41, a packing 60 is provided, which closes up airtight the space between the outer diameter of disc 41 and circular casing 23.

A packing 61 is provided on top of disc 30, which fits around the openings on same disc, and this packing being kept in place by countersunk screws 62.

The threaded openings in disc 30 and disc 41 are all spaced in a uniform arrangement, as shown in Figures 4 and 6.

Tubes 64 have on their lower end 65 a thread 66, which engages the threaded openings 42 in disc 30 41. Adjacent to the upper end of thread 66, the previously mentioned tubes are provided with a small projection 67, which is to rest firmly and airtight if the tubes are screwed down on top of the beforehand placed washers 68, which fit 35 around the openings on top of disc 41.

The previously mentioned tubes 64 have an offset 69 towards the inside above projection 67, and another offset towards the inside 70 near their top 71. The top 72 is square to allow screwing by key or similar tool. Into said tubes a thin rubber tube 73 is inserted, as shown in Fig. 5; this rubber tube has on its lower end a thickened collar 74, to rest and be held airtight in place at offset 69 on the inside of metal tube 64. This 45 rubber tube reaches upward about one half the length of the tubes 64, where same rubber tube is thickened solid 75, and the greater portion of the solid piece ending in a stick 76.

When air pressure is provided in the inner 50 tube, the thin portion 77 of the rubber tube will expand upward until the thickened solid offset 78 of the rubber tube contacts the inside offset 70 of the metal tube 64. Having thereby forced the rubber stick well above the top of 55 tube 64, which top is provided with an opening 79 for letting pass through the previously mentioned rubber stick, as shown in dotted lines 80 in Fig. 5. Any other similar suitable method can be provided on the same principle.

The casing 23 is placed through the opening (porthole) of a suitable rim 81. The rim may be reinforced around the opening (porthole), or widened, or both, as the opening (porthole) in the rim will have a greater diameter, as the openings (portholes) in the rims for the present valves, and the casing 23 kept securely in place by a nut screw 82, which fits over the outside thread 83 on casing 23. Said nut is screwed down on top of a suitable washer 84 placed on the rim. The four obtuse angles 21 on the casing 23 are provided to give resistance when nut 82 is applied over casing 23, thereby effecting a tightening of the casing as well as the inner tube to the rim. Any type of outside tire casings 85 may 75

be used, if the circular casing 23 will pass through the collar of the tire casing, otherwise if found of advantage a widened opening on the collar of the outer tire casing can be provided, so that the 5 collar will not interfere with the circular casing 23, or obtuse angles 21.

A suitable dust cap 87, part of the top can be provided with transparent material 88 in order to avoid a screwing off, of the dust cap when 10 checking the end pieces (sticks) 76 of the rubber tubes, is provided over casing 23; the lower end of the dust cap resting firmly on a suitable washer 89, which is provided on top of nut 82.

An outside threaded ring 90 is provided with 15 four vertical projections (lugs) 92 to facilitate the screwing by hand or suitable tool. This ring is for bringing to a check disc 41 when tubular screw is turned upward, so bottom of disc 41 will clear top of washer 61.

20 In the depressed space on top of disc 41 in between the lugs 48 a suitable washer or packing 93 is provided.

To inflate the inner tube, the hose of an air 25 pressure system or a hand pump is placed in the usual manner over valve 44; the same usual way applies for the taking of air pressure by a gauge, but before letting in the air pressure, or the taking of air pressure by gauge, the tubular screw has to be turned upward until the bottom of 30 disc 41 will clear the packing 61, as will be noted on Fig. 4. After the inner tube is inflated and the tubular screw is screwed down firm on top of packing 61, all the outer circles of the threaded openings 42 on bottom of disc 41, encircle airtight 35 all the threaded openings 31 on top of packing 61 of disc 30, thereby creating not only a free air pressure passage between the identical cells in the inner tube and the small rubber tubes 73 provided in tubes 64, but simultaneously also prevent an interchange of air pressure either 40 between the cells, or between the small rubber tubes. This is of utmost importance and one of the main features of my invention, as it affords an easy identification at the end of the rubber 45 sticks 76, as any stick whose corresponding cell or cells have become punctured, blown out or otherwise damaged so that they lost their air pressure, will descend flush to the top 71 of the tubes 64, as shown in Fig. 5.

50 If the case should be that the stick on the rubber tube in one of the metal tubes indicate, that a cell became punctured, blown out or otherwise lost its air pressure, the tube 64 and the inserted rubber tube 73 of the concerned one 55 can be removed, and the concerned hose opening (air passage), respectively the opening in disc 30 can be closed up airtight by a plug screw 97, which is screwed down on the threaded opening 31 of disc 30 until the projection 98 of the plug screw rests firmly on top of packing 61. This 60 plug screw is of a length to reach well above the top of disc 41 when same is turned upward to clear with its bottom the top of packing 61. The removed tube 64 is then replaced by tube 96, 65 which has a closed square head; this tube being of a length and diameter to facilitate the placing over the previously mentioned plug screw, and being screwed down until the projection 97 rests firmly on washer 68 and an airtight closure 70 is effected. Tube 64 and tube 96 and plug screw 97 are all provided with the same sized square head, so any single key will fit any one of them. After the previously mentioned plug screw for 75 the opening in disc 30, and the closed tube 96 leading to the punctured or otherwise damaged

cell are in place, the inner tube (the not damaged cells) if wanted can be more inflated by turning the tubular screw upward, so that the bottom of disc 41 will clear the top of packing 61, and no air pressure is lost through the punctured or otherwise damaged cell or cells, as shown in Fig. 8.

If the sticks of the rubber tubes indicate that all cells in the inner tube are in good order, but more inflation is wanted, the tubular screw 50 10 has to be turned upward to obtain sufficient clearance between the bottom of disc 41 and packing 61, and the hose of an air pressure system or a hand pump placed over the valve 44 in the usual manner.

The cells of the inner tube are provided on the outside with consecutive numbers, like 1, 2, 3 etc., and identical numbers are provided on top of disc 41 near the corresponding (specific) threaded openings, to conform with the specific cells, 20 so for instance, the threaded opening numbered 1 in the upper disc 41 (where the metal tubes are screwed in) leads to the cell in the inner tube numbered 1; the threaded opening in the upper disc (41) numbered 2, leads to the cell in the inner tube numbered 2, and so on. This identical numerical arrangement on the outside of the cells of the inner tube and on top of disc 41, gives at a glance the particular cell or cells punctured or otherwise damaged.

30 Various changes or alterations in the details of my invention will readily suggest themselves, and I do not limit my invention to those details herein shown and described but hold that I may make such alterations or changes as shall fairly fall within the scope of the specification and the appended claims therein as I deem necessary to the successful practice of my invention. For instance the number of tubes mounted on the movable disc may be changed as desired, it being 40 simply necessary that there be a plurality, or more than one.

What I claim is:

1. In an inflating unit for pneumatic tires or inner tubes with a plurality of compartments the 45 unit comprised of a casing, a perforated stationary disc, a perforated vertically movable disc, having an airtight enclosure moving on a screw-bolt by means of an elongated nut, a valve mounted on such vertical movable disc for inflating and deflating through feed lines all compartments simultaneously, metal tubes with suitably inserted rubber tubes ending in a solid end mounted on such movable disc for each compartment, the rubber tubes inside the metal tubes 50 directly communicating through feed lines with the respective compartments in the pneumatic tire or inner tube, when the two discs are locked together in airtight relation and giving a signal if its respective compartment in the pneumatic tire or inner tube is inflated—by forcing the solid endstick of the rubber tube upward, the location of a puncture in the pneumatic tire or inner tube being identified by having the compartments in the pneumatic tire or inner tube, or 55 both and their respective communicating rubber tubes inside the metal tubes numbered correspondingly.

2. In an inflating unit for pneumatic tires or inner tubes with a plurality of compartments, the 70 unit comprised of a casing enclosing airtight a stationary disc a vertically movable disc moving on a screwbolt, and in such vertically movable disc means by which an elongated nut rotates, and the elongated nut engaging a thread on the 75

screwbolt; a valve mounted on such vertically movable disc for inflating the compartments simultaneously, metal tubes with suitably inserted rubber tubes with a solid endpiece for each compartment mounted on such vertically movable disc; the inside of the rubber tubes having direct communication with their respective compartments in the pneumatic tire or inner tube when the two discs are locked together in airtight relation and signaling if the respective compartments in the pneumatic tire or inner tube are inflated or deflated by forcing the end of the rubber tube upward or letting it down as the case may be, the respective compartments identified by a corresponding numbering arrangement of the compartments with the rubber tubes inside the metal tubes.

3. In an inflating unit for pneumatic tires or inner tubes with a plurality of compartments, the

unit comprised of a casing which encloses a stationary disc, a vertically movable disc having an airtight enclosure mounted on a bolt, a valve for inflating all compartments simultaneously, a plurality of metal tubes mounted on the movable disc, with suitably inserted rubber tubes ending in a solid stick mounted on the movable disc; the rubber tubes inside the metal tubes having directly communication through feed lines with the respective compartments in the pneumatic tire or inner tube when the two discs are locked together in airtight relation, thereby preventing an interchange of air pressure and giving a signal if its respective compartment in the pneumatic tire or inner tube has air pressure—by forcing the solid endstick of the rubber tube through an opening in the top of the metal tube.

SIEGFRIED LIBO.
